UNITED STATES PATENT OFFICE

90,823

DESIGN FOR A SHOE SHINER

Louis J. Venerose, Bronx, N. Y.

Application April 25, 1931. Serial No. 39,624

Term of patent 3½ years

To all whom it may concern:

Be it known that I, LOUIS J. VENEROSE, a citizen of the United States, and resident of the Bronx, in the county of Bronx and State of New York, have invented a new, original, and ornamental Design for a Shoe Shiner, of which the following is a specification.

In the accompanying drawing:—

Fig. 1 is a perspective view of a shoe shiner constructed according to this invention, and

Fig. 2 is a perspective view showing the shoe shiner in a closed position.

I claim:—

The ornamental design for a shoe shiner as shown.

LOUIS J. VENEROSE.
